TUBULAR RAIL MEMBER

William H. Neely, Cleveland, Ohio, assignor to
The Universal Wire Spring Company, Cleve-
land, Ohio, a corporation of Ohio

Application September 21, 1949, Serial No. 116,999

9 Claims. (Cl. 155—179)

1

This invention relates in general to supports for upholstered spring constructions and, more particularly, to rails adapted to support the individual springs of spring constructions assembled from sinuously corrugated wire springs.

The primary object of the invention is the provision of a rail member adapted to mount sinuously corrugated wire springs, the rail member including hook-shaped means adapted to engage one of the straight wire portions of a sinuously corrugated wire spring for supporting the spring at a point spaced from the end thereof, and cooperating locating and locking means arranged to engage one of the loops of such wire spring arranged adjacent to the said straight wire portion thereof to locate the spring, lock same in proper position, and permit quick, easy mounting and demounting of such spring.

Another object of the invention is the provision of a rail member adapted to mount sinuously corrugated wire springs, the rail member including a portion provided with hook-shaped means adapted to engage one of the straight wire portions of a sinuously corrugated wire spring for supporting the spring at a point spaced from the end thereof, and cooperating locating and locking means on said portion adapted to engage one of the loops adjacent to the said straight wire portion of such spring, to locate the spring and lock same in proper position.

A further object of the invention is the provision of a tubular rail member for mounting sinuously corrugated wire springs, the rail member being assembled from two substantially symmetrically shaped sheet metal strips having Z-shaped cross section, the strips being engaged with each other in inverted position and one of said strips including at one side edge an offset portion providing said rail member with hook-shaped means adapted to engage one of the straight wire portions of a wire spring for supporting same, and furthermore including a pair of cooperating locating and locking means arranged to engage one of the loops of the sinuously corrugated wire spring adjacent to the said straight wire portion thereof.

With the above and other incidental objects in view, the invention has other marked improvements and superiorities which radically distinguish same from presently known structures. These improvements and superior characteristics, embodying certain novel features of construction, are clearly set forth in the appended claims and the preferred embodiment of the invention hereinafter shown with reference to the accompanying drawing forming part of the specification.

2

In the drawing:

Fig. 1 is a perspective view of a rail member constructed in accordance with the invention, the rail member mounting the upper portion of a sinuously corrugated wire spring;

Fig. 2 is a front view of the rail member shown in Fig. 1;

Fig. 3 is a sectional view on line 3—3 of Fig. 2; and

Fig. 4 is a sectional view on line 4—4 of Fig. 2.

Referring more in detail to the exemplified form of the invention shown in the drawing, reference numeral 2 denotes a tubular rail member which is assembled from two elongated sheet metal strips 3 and 4 of Z-shaped cross section. These sheet metal strips which each include a web 5 having integrally extended from opposite edges thereof flanges 6 and 7, of which flange 6 is substantially wider than flange 7, are secured to each other in inverted position so that the narrower flange of one strip is positioned opposite the wider flange 6 of the other strip. The resulting tubular rail member is formed with a tubular body 8 provided with reinforcing flanged portions 9 and 10 extended from body 8. One of the flanged portions, to wit flanged portion 9, is formed with hook-shaped means 11 and locating and locking means 12. The hook-shaped means 11 which permit attachment of sinuously corrugated springs 13 to flanged portion 9, when a straight cross member 14 of such wire spring is engaged with said hook-shaped means, is formed by cutting wider flange 6 of strip 3 at predetermined places to provide such flange with a tongue portion 15 and laterally offsetting such tongue portion. The width of tongue portion 15 is approximately equal to the length of the straight cross members 14 of sinuously corrugated wire springs 13 and the offset of said tongue portion is approximately equal to the gage of the wire of spring 13 so as to properly seat the cross members between tongue portion 15 and the narrower flange 7 of strip 3. The locating and locking means 12 which effects locating and locking of springs 13 by engagement with one of its loops 16, the loop arranged adjacent to the said straight cross member 14, is formed by a protuberance 17 extended from the wider flange 6 of strip 3 and a laterally bent-out portion 18 arranged adjacent to the tongue portion 15 of flange 6 of strip 3.

The protuberance 17 and bent-out portion 18 which cooperate in locating the spring axially on tubular rail member 2 and tend to hold such spring in proper position on tongue portion 15 by preventing accidental removal of the spring from said tongue portion, permit quick and ready

demounting of the spring from the rail member by slight forcible downward tilting of the said loop 16 over protuberance 17 to permit lateral movement of the spring toward the right and then removal of the spring from the tongue portion 15 by pulling such spring out of the seat formed by the tongue portion. Mounting of the spring is effected by reversing the steps delineated above.

The described tubular rail member can readily be used for constructing so-called open frames for seat and back constructions, or elongated portions of these tubular rail members can directly be attached to a supporting member as for example the frame structure of an automobile.

Having thus described my invention:

What I claim is:

1. A rail member for supporting sinuously corrugated wire springs comprising a body having one edge cut at spaced places and the portion between said cuts bent to form a hook-shaped supporting means adapted to seat one of the loop-connecting cross members of a sinuously corrugated wire spring, and a pair of cooperating spaced locating and holding means on said body arranged adjacent to one cut in the edge thereof adapted to engage opposite sides of the wire of a wire loop of such sinuously corrugated wire spring and prevent lateral shifting of such loop.

2. A rail member as described in claim 1, having said pair of spaced locating and holding means positioned so that a line through said pair of spaced locating and holding means angularly intersects a line through the seat formed by said hook-shaped supporting means.

3. A rail member as described in claim 2 wherein in said pair of spaced locating and holding means for the wire of said wire loop of said sinuously corrugated wire includes a protuberance and a stop member arranged in spaced relation with respect to said protuberance.

4. A rail member for supporting sinuously corrugated wire springs comprising a tubular body, reinforcing flanges extended from said body in opposite directions, hook-shaped supporting means in one of said flanges adapted to seat one of the loop-connecting cross members of a sinuously corrugated wire spring and a pair of spaced locating and holding means on said one flange adjacent to one side of said supporting means adapted to engage opposite sides of the wire of a wire loop of such sinuously corrugated wire spring and prevent lateral shifting of such loop.

5. A rail member for supporting sinuously corrugated wire springs comprising a tubular body, reinforcing flanges extended from opposite sides of said body, hook-shaped means in one of said flanges adapted to seat one of the loop-connecting cross members of a sinuously corrugated wire spring, and a pair of spaced locating and holding means in said one flange arranged adjacent to one side of said hook-shaped means, said locating and holding means adapted to engage opposite sides of the wire of one of the loops extending from the said one loop-connecting cross member of said spring and hold such loop against lateral movement.

6. A rail member for supporting sinuously corrugated wire springs comprising two elongated metal strips of Z-shaped cross section assembled to form a tubular body having flanges extended therefrom in opposite directions, hook-shaped supporting means in one of said flanges adapted to seat a loop-connecting cross member of a sinuously corrugated wire spring, and a pair of spaced locating and holding means on said one flange arranged to engage opposite sides of the wire of a wire loop of such sinuously corrugated wire spring and hold such loop to prevent lateral shifting of the spring.

7. A rail member for supporting sinuously corrugated wire springs comprising elongated metal strips of Z-shaped cross section assembled to a tubular body with flanges extended therefrom in opposite directions, open hook-shaped supporting means for a sinuously corrugated spring arranged in one of said flanges by cutting the edge thereof in spaced places and shaping the cut portion to a support for a sinuously corrugated wire spring when seating one of its loop-connecting straight portions in said supporting means, and a pair of spaced, loop-engaging and holding members on said one flange arranged adjacent to one side thereof to engage opposite sides of the wire of a loop of said spring adjacent to its supported loop-connecting straight portion.

8. A rail member as described in claim 7, wherein in the loop-engaging and holding members on the said one flange of said body are formed in one of the Z-shaped strips and consists of a protuberance and a lateral extension spaced from said protuberance approximately the diameter of the wire of the sinuously corrugated wire springs to be supported by said rail member.

9. A rail member for supporting sinuously corrugated wire springs comprising elongated metal strips of Z-shaped cross section assembled to a tubular body with flanges extended therefrom in opposite directions, said Z-shaped metal strips including a web portion having extended therefrom two flanges one of which is wider than the other one, one of said metal strips including in its wider flange an outwardly offset portion adapted to form a hook-shaped seat adapted to support a loop-connecting straight portion of a sinuously corrugated wire spring, said wider flange of said one metal strip additionally including adjacent to said hook-shaped seat a pair of spaced, loop-engaging and holding means adapted to engage opposite sides of the wire of the loop adjacent to a supported loop-connecting straight portion of a sinuously corrugated wire spring.
